US00D731541S

(12) **United States Design Patent**
Lee

(10) **Patent No.:** US D731,541 S
(45) **Date of Patent:** ** Jun. 9, 2015

(54) **DISPLAY SCREEN OR PORTION THEREOF
WITH ICON**

(71) Applicant: **Samsung Electronics Co., Ltd.**,
Suwon-si (KR)

(72) Inventor: **Seung-Myung Lee**, Seoul (KR)

(73) Assignee: **Samsung Electronics Co., Ltd.**,
Suwon-si (KR)

(**) Term: **14 Years**

(21) Appl. No.: **29/456,168**

(22) Filed: **May 29, 2013**

(30) **Foreign Application Priority Data**

Feb. 23, 2013 (KR) 30-2013-0009593

(51) **LOC (10) Cl.** **14-04**

(52) **U.S. Cl.**

USPC **D14/489**

(58) **Field of Classification Search**

USPC D14/485-495; 715/703, 715, 727, 763,
715/773, 776, 779, 839, 810, 811, 812, 813,
715/814, 815, 821, 825, 828, 833, 835, 836,
715/837, 838, 840, 846, 847, 864, 963, 974,
715/976, 977

CPC G06F 3/0482; G06F 8/34; G06F 3/04817;
G06F 3/048
